UNITED STATES PATENT OFFICE.

ADELMER M. BATES, OF CLEVELAND, OHIO, ASSIGNOR TO BATES VALVE BAG COMPANY, OF CLEVELAND, OHIO, A CORPORATION OF WEST VIRGINIA.

VALVE-BAG.

No. 810,818.

Specification of Letters Patent.

Patented Jan. 16, 1906.

Application filed February 2, 1903. Serial No. 141,549.

To all whom it may concern:

Be it known that I, ADELMER M. BATES, a citizen of the United States, residing at Cleveland, in the county of Cuyahoga and State of Ohio, have invented a certain new and useful Improvement in Valve-Bags, of which the following is a specification.

My invention relates to valve-bags, and has for its object to provide certain new and useful valve-bags and improvements therein, as hereinafter described and referred to.

I have illustrated my invention in a diagrammatic manner, and in the drawings Figure 1 is a bottom view of the bag in a partially-unformed state. Fig. 2 is a similar view with the parts folded in upon each other to complete the bag. Fig. 3 is a cross-section on line 3 3, Fig. 2. Fig. 4 is a longitudinal section on line 4 4, Fig. 2. Fig. 5 is a similar view with the parts shown in their position during the filling process. Fig. 6 is a detail view of the parts illustrated in Figs. 4 and 5 with the filling-tube removed. Fig. 7 is a view of a bag-tube with the valve extension-piece in the position which it would occupy if applied to the tube before the folding is done. Fig. 8 is a detail cross-section on line 8 8, Fig. 7.

Like parts are indicated by the same letters in all the figures.

AA are the side portions of the bag, which in the case illustrated is made with a so-called "satchel-bottom"—that is to say, the bag-tube being collapsed so that the side portions are in contact with each other, the two triangular end portions BB are folded in toward each other, and the two bottom portions CC are formed by creasing the side portions along the line D. In one form of the bag the two side portions can be creased along the lines EE and be folded in toward each other, and then when the parts are pasted together it will be seen that the bottom is completely formed. Such bags are commonly thus finished at the bottom, and the material is then put into the bag and the bag is tied at the top. In the case shown here to illustrate my invention Fig. 1 indicates the upper portion of the bag, the lower portion of which has already been completely formed so as to be completely closed. A piece of material F, shaped as shown and adapted to form what I shall call an "extension-valve," is now inserted between the two pieces CC and the piece B, as indicated, and

when the pieces are folded together it is obvious that the piece of material F will be folded up with the portions CC of the bag. This is illustrated in Fig. 2, where the parts have been so brought together. The parts in this process of folding are gummed to a certain extent—that is to say, the left-hand portion of one part C is gummed and folded over onto the part B and the inner portions and parts CC. The other part C is now gummed along its whole length and folded on top of the first part C, and thus the parts are all brought together in the position shown in Fig. 2; but there is an opening through the folded portions of the material F, and this is the valve-opening protected by the collapsible extension-valve part F. The filling-tube G is shown as inserted through this opening. The tube G may be supplied with spreading ribs G' or any structure which will tend to keep the valve-opening open or partially open about the tube, and the parts are preferably so related that the valve-opening is larger in cross-section than the tube. All this is indicated in Fig. 3. This arrangement of parts is desirable when the material of which the bag is composed is practically impervious to air—as, for example, when it is made of paper or waterproof material. In such cases the valve extension is preferably made of material differing from the material of the bag. In other words, in a paper bag a cloth valve extension-piece can be employed. This piece can be gummed or secured in any desired manner, if such securing is found necessary, to the bag portions when it is put in place, as indicated in Fig. 1.

When the parts are folded together as indicated in Figs. 2 and 3, they are arranged so that on a cross-section of Fig. 3 the first fold of material, beginning at the top, is one of the parts C, the next is the extension-piece F, the next is another part C, the next is the extension-piece F, under which lies the tube G, and at the bottom is again the extension-piece F.

As previously suggested, the arrangement of parts here shown is to be taken merely as diagrammatic and not in any sense as limiting me to the particular form and arrangement here illustrated.

The use and operation of this invention and its advantages I will now proceed to suggest in part. In the first place, I can thus

provide, by means of this flexible extension, a paper or other bag practically impervious to air with a suitable valve device. This valve device may of course be of any desired material and the same or a different material from that of the bag proper; but in the ordinary form of the device there will be a paper bag, such as the ordinary paper flour-bag, accompanied by the inwardly-extending flexible cloth-formed valve. In the case of such bags, where they are filled by means of a tube or by a narrow stream, it is obvious that the opening through which the filling takes place should be larger than the filling-tube, so that the air within the bag can escape around the tube. This would not be true, of course, if the sides of the bag were not impervious to air. Thus with a cloth bag the valve might fit closely around the tube. With a paper bag it ought not to do so; but if the opening is larger than the tube then the escaping air will carry with it a quantity of flour or other such material as may be in the process of being filled into the bag. The flexible material which I employ should therefore be in most cases of a nature to permit the air to pass, but so as to act as a screen and prevent the powder or flour from passing with such current of air. Thus the flexible or cloth valve of a paper bag, such as illustrated in Fig. 5, will close around the tube and act as a screen, permitting the air to pass out, while at the same time preventing the escape of flour or other material.

The valve-opening may be expanded and kept open by the ribs G' G', shown on the tube, though of course any other sort of extending device could be used and it could be separate from or attached to the tube, as desired. The extension-valve device can be formed of any small piece of material and in ordinary practice would be made of waste or scrap material.

In order to get the long inwardly-projecting valve, it would be necessary, whatever the material, to fold down the parts B B of the bag-tube so as to bring their ends inwardly toward the center or middle line of the bag; but when this is done then the bottom of the bag becomes wide, and this is the manner in which such bags are frequently made. By my construction I am enabled to get a long opening for the valve-opening with a narrow bottom and top for the bag, and thus can produce a bag to hold a given weight of material with a shorter tube than if I endeavored to obtain the valve feature without the addition of the extension-piece. Thus in a case where the material of the bag was a proper material to form a valve I could get such valve-opening without any extension-piece; but in that event I should have to use a longer bag-tube, and thus would have a great deal of waste material. At the same time the valve-opening would be correspondingly widened, so

that the advantage obtained by increasing the length of the opening would be offset by increasing its width. By the method here shown I obtain a long and narrow opening into the bag, and when this opening is protected by the inward extension it becomes very effective as a valve.

There is another feature of great advantage in my device, and that is this: the valve extension-piece F would naturally be made of suitable material to form a valve, and this would be important if it were associated with a bag the material of which was not suitable for such valve. If, for example, I had a paper bag, it is obvious that the two faces of paper coming together would not make a good closure; but if to this I add the valve extension-piece F of cloth then when the tube is withdrawn the two faces of cloth come together, as indicated in Fig. 6, and form a very complete closure. I can make any size of valve I desire by this means by simply varying the length of the extension-piece F, and I can fold it into the material while the bag is in the process of being formed or otherwise. Moreover, it greatly strengthens the bag, if the same should be made of weak material, about the point where the material is introduced into the bag, which of course is the very point where such weak-material bag would need strengthening.

My arrangement is peculiarly valuable in the case of bags upon which printed matter is placed, for obviously when the bags are tied at the top a large part of the upper portion of the bag is creased and wrinkled, so as to greatly reduce the area suitable for printing. It is not uncommon for bags of this nature bearing the printed brand of well-known manufacturers to be untied and emptied and to be then filled with an inferior grade of material. This can be prevented by the use of my bag, for the printed matter will come near the top, and the structure of the bag is such that it has practically to be destroyed in order to be emptied, and any attempt to close it again would necessarily result in revealing the fraud.

The valve extension-piece may be of the same or different material as compared with the body of the bag. It may be of cloth applied to a paper bag. It may be flexible and made so as to form a screen about the tube to prevent the escape of material through the enlarged opening about the tube. It results in bringing the two extension and preferably cloth surfaces together to close the valve when the bag is filled. It may be secured in any desired manner by pasting or by gumming or sewing and at any desired time during the process of the making of the bag or at other times, according to the form of the bag. It may be made of waste material and any-sized bag can be used. The result is a bag narrow at the top and bottom, with an in-

creased printing area and with a reinforcing or strengthening effect about the valve-opening, and it renders the reuse of the bag difficult, if not impossible.

- 5 The valve extension-piece surrounds the valve-opening, and thus strengthens it at all points, and might be used without any material extension to form a valve proper, but simply to serve as a binding or strengthening 10 part for the opening between the walls of the bag itself.

I claim—

1. A valve-bag, comprising a body of comparatively inflexible material, with a valve-opening therethrough, and an inner valve extension composed of comparatively flexible 15 material.

2. A valve-bag, comprising a body of material comparatively impervious to air, with 20 a valve-opening therethrough, and an inner valve extension composed of material which permits the air to pass.

3. A valve-bag, comprising a body of material comparatively impervious to air, with 25 a valve-opening therethrough, and an inner valve extension composed of material which permits the air to pass, such material being flexible.

4. A valve-bag, comprising a body of material comparatively impervious to air, with 30 a valve-opening therethrough, and an inner valve extension composed of material which permits the air to pass, such material being flexible while the material of the bag is comparatively inflexible.

5. A valve-bag, comprising a bag-body, with a top portion consisting of parts folded together substantially as shown and so as to leave an opening into the bag between such 40 folded parts, and an extension-piece applied to said bag at the inner end of such opening.

6. A valve-bag, comprising a bag proper, with top portions folded and secured together, and a valve extension part inserted in such 45 folds, so as to leave a valve-opening formed partly by the material of the bag and partly by such extension.

7. A valve-bag, comprising a bag proper of paper, with an opening thereinto, and a 50 strengthening-piece of cloth surrounding said opening.

8. A valve-bag, comprising a bag proper of paper, with an opening thereinto, and a strengthening-piece of cloth surrounding said 55 opening, said strengthening-piece projecting inwardly to form a valve extension.

9. A valve-bag, comprising a bag proper of relatively inflexible material, with an opening thereinto, and a strengthening-piece sur-

rounding said opening, said strengthening piece projecting inwardly to form a valve extension and of flexible material.

10. A valve-bag, comprising a bag proper, with narrow folded-over portions lying one on the other, said portions secured to each other except at one end, so as to leave an opening between them, and a strengthening fabric surrounding such opening.

11. A valve-bag, comprising a bag proper, with narrow folded-over portions lying one on the other, said portions secured to each other except at one end, so as to leave an opening between them, and an inwardly-projecting valve extension surrounding such opening.

12. A valve-bag, comprising a bag proper, with narrow folded-over portions lying one on the other, said portions secured to each other except at one end, so as to leave an opening between them, and an inwardly-projecting strengthening-valve extension portion surrounding the opening, strengthening the same and forming an inner valve portion.

13. A valve-bag, having a square folded top, a filling-opening in said top in position to be closed by one of the folds of said top, and a strengthening-piece adjacent to said fold, as set forth.

14. A paper valve-bag, having a diamond-folded top, a filling-opening in said top, said opening adjacent to and in position to be closed by one of the primary folds of said top, and a cloth strengthening-piece adjacent to said primary fold, as set forth.

15. A valve-bag, having a square folded top, a lateral filling-opening extending between the folds of said top and in position to be closed by one of said folds, and a cloth strengthening-piece adjacent to the valve fold, as set forth.

16. A paper valve-bag, having a diamond-folded top, a lateral filling-opening extending between the folds of said top and in position to be closed by one of the primary folds, and a cloth strengthening-piece adjacent to the valve fold, as set forth.

17. A paper valve-bag, having a diamond-folded top, a lateral filling-opening extending between the folds of said top and in position to be closed by one of the primary folds and a cloth strengthening-piece adjacent to and extending beyond the edge of the valve fold, as set forth.

ADELMER M. BATES.
